UNITED STATES PATENT OFFICE.

CHARLES S. MILLS, OF MIDDLETOWN, NEW YORK.

PRINTING-PLATE BASE.

1,031,803.

Specification of Letters Patent. Patented July 9, 1912.

Application filed January 26, 1912. Serial No. 673,624.

To all whom it may concern:

Be it known that I, CHARLES S. MILLS, a citizen of the United States, residing at Middletown, county of Orange, and State 5 of New York, have invented certain new and useful Improvements in Printing-Plate Bases, of which the following is a specification.

This invention relates to novel means for 10 justifying printing plates of different thicknesses on bases.

As is well known stereotype, electrotype or similar plates are considerably thicker than etched plates, the former being generally 11 point, while the latter are 16 gage. 15 Thus in justifying these two different kinds of plates, the former requires a thinner block than the latter, the requirement being that the combined thickness of the thick 20 plate and its block is equal to the combined thickness of the thin plate and its block. By my invention, one and the same supporting means will justify both kinds of plates, so that multiplicity of parts is ob- 25 viated and simplicity in manipulation is insured.

In the accompanying drawing: Figure 1 is a plan of a base embodying my invention showing it applied to a relatively thin plate; 30 Fig. 2 an end view thereof; Fig. 3 a cross section through a single supporting block showing a superposed relatively thin plate; Fig. 4 a similar view showing a superposed relatively thick plate; Fig. 5 a perspective 35 view of the block; Fig. 6 a similar view of one of the end clamps; Fig. 7 an end view of a pair of longitudinally aligned blocks with an interposed filler, and Fig. 8 a perspective view of the filler.

40 The supporting block 10 is adapted to support either a relatively thin printing plate 11, such as an etched plate or a relatively thick printing plate 12, such for instance as an electrotype plate, both plates 45 being justified and then set in a chase ready for stereotyping. Block 10 is of parallelopipedal shape with rectangular base and its length corresponds substantially to the width of a column. The height of the block 50 is greater than its width, the difference between height and width being equal to the difference between the thicknesses of plates 11, 12. That is to say the thickness of thin plate 11 plus height x of block 10 is equal 55 to the thickness of thick plate 12 plus width y of the block. Thus if plate 11 is to be

justified block 10 is placed upon its side y as a base (Fig. 3) while when plate 12 is to be justified the block is placed upon its side x (Fig. 4). It will thus be seen that 60 one and the same block is adapted to support both kinds of plates at a common level, so that the use of differently sized blocks for plates of different thickness is entirely obviated. Plates 11, 12 are generally of a 65 length to extend over a number of blocks 10 as illustrated in Figs. 1 and 2. The ends of the plates are beveled as at 13, such beveled ends being adapted to engage clamps 14, removably fitted to the flanking 70 blocks 10. Each clamp 14 comprises a flat plate-like lower section 14^a which corresponds in height substantially to the width y of block 10, and of a beveled flange 14^b, the height of which is nearly equal to that 75 of thick plate 12.

Means are provided for removably attaching clamp 14 to either the side x or y of block 10. These means consist of a pair 80 of pins 15 projecting from one face of clamp section 14^a and adapted to engage either of a pair of apertures 16 or 17 formed in two adjoining sides x and y of block 10. When a thick plate is to be justified, clamp 14 is attached to side y (Fig. 4) while when a thin plate is to be justified the clamp is attached to side x (Fig. 3). It will be seen that in the latter case, the lower portion of flange 85 14^b is overlapped by the upper section of side x , so that the height of the protruding upper portion of flange 14^b corresponds almost to the thickness of plate 11. It is preferred to form the apertures 16, 17 in all 90 of the blocks 10, so that either one of said blocks is adapted for use as a flanking block. 95

Plates 11, 12 are frequently of a width to extend over two or more columns, in which case a number of blocks 10, must be arranged end to end in longitudinal alinement (Fig. 7). Here it is necessary to interpose between each pair of adjoining blocks, a filler to blank the column. This filler consists of a plate 18 corresponding in height and length to the height and width of block 10. To sustain the filler in position, it is provided with a laterally extending pin 19 adapted to removably engage an aperture 20 formed in the end of block 10.

100 It will be seen that by the invention described, ready means are provided for justifying variously dimensioned printing plates 110 within the chase, so that the use of a multi-

plicity of differently shaped supporting blocks is entirely obviated. As the same end clamps and the same fillers may also be used for differently dimensioned plates, a 5 large saving in working equipment is effected, the necessity of making different selections for different plates is avoided, and simplicity in manipulation is insured.

I claim:

- 10 1. A support for printing plates of different thicknesses, comprising a block of greater height than width, an end clamp, and means for removably securing said clamp to either of two adjoining sides of 15 said block.
2. A support for printing plates of different thicknesses, comprising a block of greater height than width, and having apertures in two adjoining sides, and an end 20 clamp having pins adapted to engage said apertures.

3. A support for printing plates of different thicknesses comprising a block of greater height than width, a flanged end clamp of a height nearly equal to the aggregate width of the block and the thickness of a relatively thick plate, and means for removably securing said clamp to either of two adjoining sides of the block.

4. A support for printing plates of different thicknesses comprising a block of greater height than width, a filler corresponding in height and length to the height and width of the block and adapted to be interposed between the ends of a pair of 35 said blocks, and means for removably securing said filler to one of said blocks.

CHARLES S. MILLS.
